UNITED STATES PATENT OFFICE.

GEORGES GUSTAVE OCTAVE MARICHAL, OF PARIS, FRANCE.

DOOR-STOP.

1,387,795.

Specification of Letters Patent. Patented Aug. 16, 1921.

Application filed October 6, 1919. Serial No. 328,713.

To all whom it may concern:

Be it known that I, GEORGES GUSTAVE OCTAVE MARICHAL, residing in Paris, France, have invented new and useful Improvements 5 in or Relating to Door-Stops, of which the following is a specification.

The invention relates to a safety stop that can be placed under a door in order to prevent the door being opened, or to give an 10 alarm if an attempt is made to force the door.

The apparatus used comprises a lever, one end of which, formed as a wedge, engages under the door, while the opposite end controls 15 an electric contact in the circuit of a bell. Thus the bell is operated when the contact closes the circuit of the bell when the door is pushed.

The accompanying drawing shows by way 20 of example a construction of a device according to the invention.

Figure 1 is a side elevation of the apparatus in longitudinal section;

Fig. 2 a back view, and

25 Figs. 3 and 4 illustrate the manner in which the two essential parts of the apparatus are formed.

The stop device comprises a base 1 provided 30 with hooks 2 and constituted by a plate which is bent at the back to form a vertical lug 14. This lug provided with an opening 13, receives at its end a block 3 of fiber or other insulating material. The block 3 carries two contacts 4 connected to 35 screw-threaded pins 5, while cylindrical washers 6 and milled nuts 7 are used for securing wires connected to the circuit of a bell or of any desired alarm device.

The base 1 is provided with two side 40 plates 8 to which are pivoted at 9 the side plates 10 of a lever 11. The front arm of the said lever is shaped as a wedge. The rear arm engages with the opening 13 of the lug 14 and is bent over at its end so as to 45 rest on the bottom edge of the opening 13, which opening moreover operates as a guide during the pivoting movement of the lever.

To the end of the said lever is secured a 50 blade 12 of chrysocal or other conducting and resilient material. The said blade

comes into contact with the contacts 4 when the front of the lever is lowered.

The manufacture of the apparatus is exceedingly simple. The base can be for instance formed by cutting a piece of steel 55 plate to the outline shown in Fig. 3, with an opening 13. The plate is then stamped out to form the hooks 2. The back is then bent upwardly to form the lug 14, and the lateral lugs are bent to form the side 60 plates 8.

The lever 11 is formed by cutting a piece of steel plate to the shape shown in Fig. 4. The lateral lugs after being bent, form the side plates 10 of the lever 11. 65

The working of the device is as follows: The hooks 2 are introduced into suitable recesses provided in the floor so as to place the front of the lever 11 against the door, the opening of which is to be prevented. If 70 the said door is pushed, it will jam on the front of the lever and offer considerable resistance to opening. Moreover the front of the lever being lowered, the rear portion will be raised, and the blade 12 will make 75 contact between the two contacts 4 so that the bell will be operated.

This device while being simple and economical in construction, insures great safety, as it is very reliable in working. 80

I claim:

A door stop comprising a base plate having an upturned end provided with an opening, and also having upturned side lugs at the opposite end; an insulating block secured on said upturned end, and provided with electrical contacts; an upper plate having a downturned end arranged in said opening, an inclined inner end, and downturned side lugs on opposite sides of said 85 inclined end and pivotally connected to the first-named lugs, and a circuit-closing plate attached to the front end of said upper plate, extending through said opening and arranged to engage the electrical contacts 90 when the inclined end of said upper plate is depressed by a door. 95

In witness whereof I affix my signature:

GEORGES GUSTAVE OCTAVE MARICHAL.
